193,400

GAMEBOARD OR SIMILAR ARTICLE

Helen Wegner, 5 Donny Terrace, Kingsville, Md.

Filed Jan. 15, 1962, Ser. No. 68,302

Term of patent 14 years

(Cl. D34—5)

The FIGURE is a plan view of a gameboard showing my new design.

The board has a conventional thickness.

I claim:

The ornamental design for a gameboard or similar article, substantially as shown and described.
